UNITED STATES PATENT OFFICE.

HENRY ZIEGLER, OF NEW YORK, N. Y.

PIANO.

SPECIFICATION forming part of Letters Patent No. 634,282, dated October 3, 1899.

Application filed March 18, 1899. Serial No. 709,622. (No model.)

To all whom it may concern:

Be it known that I, HENRY ZIEGLER, a citizen of the United States, residing in the city of New York, in the borough of Manhattan and State of New York, have invented certain new and useful Improvements in Pianos, of which the following is a specification.

This invention relates to certain improvements in grand and upright pianos by which the wooden frame is connected in a permanent and effective manner with the metal string-frame, so that the strain of the strings both in longitudinal and up-and-down directions cannot change the position either of the wooden or of the iron frame; and the invention consists of a piano in which the braces and cross-block of the wooden frame are supported on a transverse lug at the lower end of a downwardly-extending bracket of the metal string-frame and connected by fastening-screws that pass through said lug at each side of said bracket; and the invention consists, further, of the combination of the braces and cross-block of the wooden frame of the piano with the metal string-frame having a downwardly-extending bracket and a transverse lug at the lower end of said bracket, fastening-screws connecting said lug, cross-block, and braces, and a wedge between the lug and cross-block, so that a firm and reliable connection between the wooden frame and the metal string-frame of the piano is obtained.

In the accompanying drawings, Figure 1 represents a top view of the frame of a grand piano with my improved support for the wooden frame. Fig. 2 is a vertical longitudinal section on line 2 2, Fig. 1, drawn on a larger scale. Fig. 3 is a detail horizontal section on line 3 3, Fig. 2. Fig. 4 is a vertical transverse section on line 4 4, Fig. 2; and Fig. 5 is a vertical transverse section of the upper part of the string-frame of an upright piano, showing its connection with the wooden frame of the same.

Similar letters of reference indicate corresponding parts.

Referring to the drawings, A represents the bent-wood rim, and α the braces of the wooden frame, of a grand or upright piano. Two of the braces α converge toward each other and support the bass portion of the string-

frame B, while a third brace α' supports the middle and treble portions of the metallic string-frame. Connection between the braces α and α' and the metal string-frame is obtained by means of one or more downwardly-extending brackets b, which are cast integral with the metal string-frame B, near the wrest-plank end of the same, said brackets being each provided at its lower end with a lug b', that is arranged at right angles thereto and cast integral with said bracket. The inner ends of the braces α and α' and the lug b' rest against the usual cross-block d of the wooden frame and are connected therewith and with the braces α by fastening-screws d', one screw being preferably arranged at each side of the bracket through the lug b', as shown clearly in Fig. 4.

A wooden wedge e is interposed between the cross-block d and the slightly-inclined face of the lug b', said wedge being retained by the screws, so as to be prevented from dropping in case of shrinkage of the wooden braces and cross-block. The wedge e serves for producing a solid connection between the lug b' and the cross-block d. When more than one connection between the wooden frame and the metal string-frame of the piano is made, an additional brace or braces for the treble proper can be used, as shown in Fig. 1. The string-frame is then provided with as many brackets and transverse lugs as there are braces to be supported. By this arrangement the longitudinal as well as the up-and-down strain of the strings cannot change the position of either the wooden or iron frame, as both frames are firmly coupled together, so that a rigid and permanent connection between their parts is obtained.

The invention is also applicable to upright pianos, as shown in Fig. 5, in which the cross-block is interposed between the wooden braces and the transverse lug at the end of the bracket of the string-frame. By locking the wooden braces and iron frame together at one or more points the strength and rigidity of the entire structure are increased, the better support for the cross-block and braces of the wooden frame obtained, and an increased resistance of the wooden frame and metal string-frame against the strains of the strings secured.

Having thus described my invention, I

claim as new and desire to secure by Letters Patent—

1. In a piano, the combination, with the metal string-frame, provided with a bracket or brackets having a transverse lug at its or their lower ends, of the cross-block and braces of the wooden frame, and fastening-screws connecting said lug or lugs with the cross-block and braces, substantially as set forth.
2. In a piano, the combination, with the metal string-frame provided with a bracket having a transverse lug at its lower end, of the cross-block and braces of the wooden frame supported by said lug, fastening-screws connecting said lug with the cross-block and brace or braces, and an intermediate wedge-piece between the lug and cross-block, substantially as set forth.
3. In a piano, the combination, with the metal string-frame provided with a bracket and a transverse lug at the lower end of said bracket, said bracket and lug being cast integral with the string-frame, of the cross-block and braces of the wooden frame supported by said lug, a wedge interposed between said lugs and cross-block and the lug, and screws connecting said lug and wedge with said cross-block and braces, substantially as set forth.

In testimony that I claim the foregoing as my invention I have signed my name in presence of two subscribing witnesses.

HENRY ZIEGLER.

Witnesses:

PAUL GOEPEL,
M. HENRY WURTZEL.
